LOCK FOR CONTAINERS

Anton Kraus, Vienna, Austria

Application April 20, 1950, Serial No. 156,974
In Austria May 11, 1949

7 Claims. (Cl. 70—67)

1

This invention relates to a lock for containers, such as brief cases, bags, or the like.

In most of the known locks of this type, the keeper can be locked in any of three different closing positions of the container.

Extensible suitcases with parts sliding one into the other are also known, in which the position of the lid relative to the container to be closed can be adjusted at a row of catches provided at the lid so as to correspond to the degree to which the container is filled. In that known suitcase the row of catches is a part of a special telescopic device which is provided in addition to the lock and to which the keeper is hinged.

The invented lock comprises, in combination, a front plate the rear surface of which defines a recess, a longitudinal slot in said front plate for guiding a keeper having side lugs, a plurality of catches provided at the side edges of said slot and adapted to engage with said side lugs, a base plate fitting into said recess and having pins on its top face, a locking plate having bores therethrough and being provided behind the catches, means for guiding the locking plate for movement parallel to the longitudinal direction of said slot between two extreme longitudinal positions and normal to the base plate, said pins and bores being so related as to size and position that the pins will extend through said bores when the locking plate is in one extreme longitudinal position and is depressed, while such depression of the locking plate, when in any other longitudinal position, is prevented by the pins being out of alignment with said bores and engaging the bottom surface of said locking plate, a key engaging lug on said locking plate, two locking notches in said key engaging lug spaced from each other in the longitudinal direction of the slot, a bolt having an upright lug adapted to engage with either of the locking notches, depending on the respective position of the locking plate, means for preventing the bolt from movement in a direction parallel to the longitudinal direction of the slot, a return spring for urging the upright lug into engagement with the respective lug with which it is in register, and resilient means for urging the locking plate against the catches.

The drawings illustrate an embodiment of the invention, by way of example,

Fig. 1 being a top view showing the entire brief case lock according to the invention,

Fig. 2 showing the brief case lock from which the cover plate has been removed,

Fig. 3 the exposed plate of the lock, with the catch springs and the bolt,

2

Fig. 4 a longitudinal section taken along the line IV—IV of Fig. 1, and, finally,

Fig. 5 a cross section taken along the line V—V of Fig. 1.

5 The front plate 2 of the lock is fastened in the usual manner on the outside of the front wall 1 of the brief case, the fastening rivets 4 being secured against tearing out by a counter plate 3 provided on the back of the wall 1 and corresponding in contour to the cover plate 2. The keeper 6 of the brief case lock is riveted to the cover 5 of the brief case with its flat portion 6a, which embraces the edge of said cover 5.

10 15 The front plate 2 of the lock has in its front, which protrudes over the margin by which it is fastened, a longitudinal slot 7, which widens at the top and in each of whose side edges a row of saw-tooth-like catches 8 is provided. The transverse lugs 6b provided at the free end of the keeper 6, which can be introduced through the wider portion of the slot 7, can be secured in these catches, said lugs being adapted to extend below the side edges of the slot 7.

20 25 The front plate 2 and the base plate 9, the latter resting directly on the front wall 1 of the brief case and in contour exactly fitting into the cavity of the front plate 2, form the casing in which the operative parts of the brief case lock are accommodated. The base plate 9, whose side margins 9a are bent at right angles for a distance which corresponds to the depth of the cavity of the front plate, carries upright guide pins 10 for two loose leaf springs 11 which are arranged near and parallel with the side margins of the base plate and have bifurcated support ends. A locking plate 12, which is longitudinally displaceable along the longitudinal edges 9a of the base plate 9, is resiliently supported on said

30 35 springs 11 and is provided, in the region of the guide pins 10 of the base plate 9, with bores 12a which, when the locking plate 12 is in its unlocked position, that is, when the upper edges of the plates 9 and 12 are in register, are coaxial

40 45 with the guide pins 10, which are adapted to pass through said bores when the plate 12 is being depressed. The inward movement of the locking plate is limited by the abutment of a shallow depression 12b, provided on the locking plate 12 opposite the slot 7 and the catches 8 of the front plate 2, upon the base plate 9.

50 The locking plate 12 is extended at its bottom right corner to form a key engaging lug 13, which has at its right-hand corner two separate notches 13a, 13b, which correspond to the open and locking positions, respectively, of the key engaging

lug, and, at its left-hand edge, an indentation 14, whose limiting surfaces are within the range of the key-web 15.

The bolt consists of a flat slide 16, which is guided by means of oblong holes against the force of a return spring 18 transversely to the locking plate 12, at two guide pins 17 fixed below the locking plate 12 to the base plate 9 near its bottom end.

An upright lug 19 is formed at the right-hand end of the slide 16, which end forms the supporting edge for the leaf spring 18 fastened to the right-hand guide edge 9a of the base plate. Said upright lug is adapted to engage alternately with the notches 13a, b, of the key engaging lug 13. In the region around the bore 20 for guiding a key pin in the base plate 9 the top edge of the slide 16 has a circular cutting-out 21, which when the slide is in locking position is concentric with the bore 20 but is limited on the right-hand side by an edge 22 which is at right angles with the top edge of the slide and on the one hand permits of the key-web 15 being turned through approximately 270 deg. when the same has been introduced through the key-hole 23 provided in the front plate 2 (Fig. 1), while, on the other hand, said edge 22 can be engaged by the web for displacing the slide 16 against the force of the spring 18.

When the keeper 6 of the brief case closure is introduced through the enlarged portion of the catch slot 7 provided in the front plate 2, and moved downward in said slot as far as the contents of the case will permit, the transverse lugs 6b of the keeper 6, subject to the action of the locking plate 11, which is being pressed upward by the springs 11, will snap into the downward-directed, saw-toothlike catches 8 which are reached by the lugs. When the brief case is filled only unilaterally so that the top portion of the brief case and the keeper 6 are at an angle with the slot 7, these catches, into which the lugs snap, need not be in juxtaposition.

The lock cannot open unintentionally however vigorously the brief case is dangled but can open only when the locking plate 12, which resiliently rests on the springs 11, is arbitrarily pressed down.

In order to prevent the brief case lock from being opened by an incompetent person, the key is introduced into the key-hole 23 of the front plate 2 of the lock and turned through approximately 270 deg., thereby first displacing by means of the web 15 the slide 16 to the right, against the force of the spring 18, whereby the lug 19 of the slide is moved out of the lower notch 13a of the key engaging lug 13. As the key is turned further the key-web 15, engaging with the lower limiting edge of the indentation 14 in the key engaging lug 13, pulls the locking plate 12 downward until the locking nose 19 of the slide 16, subject to the force of the return spring 18, snaps into the upper notch 13b of the key engaging lug 13. In this position the locking plate 12, whose bores 12a are now outside the range of the guide pins 10 of the base plate 9, is fully supported on the pins 10 so that it cannot be displaced normal to its surface, the keeper 6 thus being prevented from being pulled out.

When the key-web 15 is turned back, in the anticlockwise sense, the slide 16 is again moved against the force of the spring 18, its locking nose 19 being thereby moved out of the notch 13b, and subsequently the key-web 15 engages with the oblique limiting edge of the cutting-out

14 of the key engaging lug so as to return the locking plate 12 into its initial position in which the slide lug 19, subject to the force of the return spring 18, snaps into the lower notch 13a of the key engaging lug 13.

What I claim is:

1. A lock for a container comprising, a front plate the rear surface of which defines a recess, a longitudinal slot in said front plate for guiding a keeper having side lugs, a plurality of catches provided at side edges of said slot and adapted to engage with said side lugs, a base plate fitting into said recess and pins attached to its top face, a locking plate having bores therethrough and being provided behind the catches, means for guiding the locking plate for movement parallel to the longitudinal direction of said slot between two extreme longitudinal positions and normal to the base plate, said pins and bores being so related as to size and position that the pins will extend through said bores when the locking plate is in one extreme longitudinal position and is depressed, while such depression of the locking plate, when in any other longitudinal position, is prevented by the pins being out of alignment with said bores and engaging the bottom surface of said locking plate, a key engaging lug on said locking plate, two locking notches in said key engaging lug spaced from each other in the longitudinal direction of the slot, a bolt having an upright lug adapted to engage with either of the locking notches, depending on whether the locking plate is in one or the other of its extreme longitudinal positions, means for preventing the bolt from movement in a direction parallel to the longitudinal direction of the slot, a return spring for urging the upright lug into engagement with the respective notch with which it is in register, and resilient means for urging the locking plate against the catches.

2. A lock as set forth in claim 1, in which said catches are shaped like saw teeth and are directed obliquely inwardly and downwardly.

3. A lock as set forth in claim 1, in which the means for guiding the locking plate comprise margins of said base plate which are upwardly bent at right angles.

4. A lock for a container comprising, a front plate the rear surface of which defines a recess, a longitudinal slot in said front plate for guiding a keeper having side lugs, a plurality of catches provided at side edges of said slot and adapted to engage with said side lugs, a base plate fitting into said recess and pins attached to its top face, a locking plate having bores therethrough and being provided behind the catches, means for guiding the locking plate for movement parallel to the longitudinal direction of said slot between two extreme longitudinal positions and normal to the base plate, the pins on the latter being arranged in two pairs, and two parallel leaf springs each of which bears with its ends against one of said pairs of pins, the locking plate with the bores therethrough being supported on said leaf springs and having a flat depression in the region of the slot, which depression serves as a guide for the keeper and for limiting the movement of the locking plate against the force of said leaf springs, said pins and bores being so related as to size and position that the pins will extend through said bores when the locking plate is in one extreme longitudinal position and is depressed, while such depression of the locking plate, when in any other longitudinal position, is prevented by the pins being out of alignment.

with said bores and engaging the bottom surface of said locking plate.

5. A lock for a container comprising, a front plate the rear surface of which defines a recess, a longitudinal slot in said front plate for guiding a keeper having side lugs, a plurality of catches provided at side edges of said slot and adapted to engage with said side lugs, a base plate fitting into said recess and pins attached to its top face, a locking plate having bores therethrough and being provided behind the catches, means for guiding the locking plate for movement parallel to the longitudinal direction of said slot between two extreme longitudinal positions and normal to the base plate, said pins and bores being so related as to size and position that the pins will extend through said bores when the locking plate is in one extreme longitudinal position and is depressed, while such depression of the locking plate, when in any other longitudinal position, is prevented by the pins being out of alignment with said bores and engaging the bottom surface of said locking plate, bolt guide pins on the lower portion of the base plate, a slide having oblong holes which extend transversely to the longitudinal direction of the slot and are in engagement with said bolt guide pins, said bolt guide pins preventing said slide from movement in a direction parallel to the longitudinal direction of the slot, a key engaging lug on said locking plate, said key engaging lug overlapping said slide, two locking notches in said key engaging lug spaced from each other in the longitudinal direction of the slot, an upright lug on said slide being adapted to engage with either of the locking notches, depending on whether the locking plate is in one or the other of its extreme longitudinal positions, a return spring for urging the upright lug into engagement with the respective notch with which it is in register, and resilient means for urging the locking plate against the catches.

6. A lock for a container comprising, a front plate the rear surface of which defines a recess, a longitudinal slot in said front plate for guiding a keeper having side lugs, a plurality of catches provided at side edges of said slot and adapted to engage with said side lugs, said front plate further defining a key hole, a base plate fitting into said recess and pins attached to its top face and defining in its lower portion a circular bore for a key pin, a locking plate having bores therethrough and being provided behind the catches, means for guiding the locking plate for movement parallel to the longitudinal direction of said slot between two extreme longitudinal positions and normal to the base plate, said pins and bores being so related as to size and position that the pins will extend through said bores when the locking plate is in one extreme longitudinal position and is depressed, while such depression of

the locking plate, when in any other longitudinal position, is prevented by the pins being out of alignment with said bores and engaging the bottom surface of said locking plate, bolt guide pins on the lower portion of the base plate, a slide having oblong holes which extend transversely to the longitudinal direction of the slot and are in engagement with said bolt guide pins, said bolt guide pins preventing said slide from movement in a direction parallel to the longitudinal direction of the slot, an upright lug on and adjacent to one of the ends of the slide, a key engaging lug on said locking plate, two locking notches in said key engaging lug spaced from each other in the longitudinal direction of the slot, said key engaging lug overlapping said slide, said upright lug being adapted to engage with either of the locking notches, depending on whether the locking plate is in one or the other of its extreme longitudinal positions, a return spring engaging with the slide at the end adjacent to which the upright lug is provided and adapted to urge said upright lug into the respective notch with which it is in register, and resilient means for urging the locking plate against the catches, the slide having a limiting edge at right angles with the longitudinal direction of the oblong holes in the slide, said limiting edge being adapted to engage a web of a key introduced through said key hole and stuck with its pin into said circular bore to enable said key to move said upright lug out of engagement with any of the locking notches, the key engaging lug having a V-shaped notch adjacent to said circular bore, said notch being adapted to engage the key web to enable the latter to effect a movement of the locking plate in the longitudinal direction of the slot.

7. A lock as set forth in claim 6, in which the locking notches on the one hand and the V-shaped notch on the other are provided on such edges of the key engaging lug which are opposite each other in the direction of the oblong holes of the slide.

ANTON KRAUS.
